UNITED STATES PATENT OFFICE.

JOSEPH K. DAVISON, OF PHILADELPHIA, PENNSYLVANIA.

DESIGN FOR A BADGE.

SPECIFICATION forming part of Design No. 21,688, dated July 5, 1892.

Application filed May 5, 1892. Serial No. 431,954. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for a Badge, of which the following is a specification, reference being had to the accompanying drawings, forming part thereof.

10 The leading feature of my design for a badge is a rim encircling a seal and stars on the face of said rim, the edge of the rim being scalloped.

In the drawings, Figure 1 represents a face view of a badge embodying my invention.

15 Fig. 2 represents a view of the reverse thereof, the ribbon being omitted.

A designates a seal with the representation of a soldier of the Continental army thereon.

B designates an eagle at the top of the seal, and C designates a scalloped rim around said seal, with stars D on the face thereof. Projecting from the scallops of the rim C at intervals are points E. On the reverse of the seal is the representation of the bust of George Washington, this, however, forming no part 25 of my design.

I claim—

The design for a badge, substantially as shown and described.

JOSEPH K. DAVISON.
